UNITED STATES PATENT OFFICE.

MICHAEL J. DEMUTH, OF DUBUQUE, IOWA.

SIGN-HOLDER.

1,359,492.

Specification of Letters Patent. Patented Nov. 23, 1920.

Application filed July 1, 1920. Serial No. 393,232.

To all whom it may concern:

Be it known that I, MICHAEL J. DEMUTH, a citizen of the United States, residing at Dubuque, in the county of Dubuque and 5 State of Iowa, have invented certain new and useful Improvements in Sign-Holders; and I do declare the following to be a full, clear, and exact description of the invention, such as will enable others skilled in the art 10 to which it appertains to make and use the same.

This invention relates to improvements in sign-holders such as are used for advertising purposes on counters in stores and in windows and the like; and it has for its object 15 to provide a simple and inexpensive device of this class which is adjustable, permitting it to hold signs of various sizes.

Another object of the invention is to generally improve upon and simplify the construction of devices of this class and to produce one which is easy adjusted, strong, durable and highly effective in use.

Other objects and advantages of the invention will be apparent during the course of the following description.

In the accompanying drawings forming a part of this specification and in which like numerals are employed to designate like 30 parts throughout the same:

Figure 1 is a front elevational view of a sign-holder constructed in accordance with my invention.

Fig. 2 is an end elevational view, taken on 35 the line 2—2 of Fig. 1, looking in the direction of the arrows.

Fig. 3 is a vertical section taken on the line 3—3 of Fig. 1.

Fig. 4 is a horizontal section taken on the 40 line 4—4 of Fig. 1.

Briefly described, the device comprises a base from which a standard rises, the latter being telescopically engaged by a vertically adjustable bar, the latter and standard carrying 45 horizontal cross arms which in turn are provided at their outer ends with card engaging members, suitable means being employed to retain the bar in various adjusted positions.

50 Referring to the drawings wherein the construction is shown in detail, it will be seen that numeral 1 designates an apertured base which is adapted to be attached by suitable fastenings on a counter or other suitable place at which a device of this class is used. The laterally bent lower end 2 of the

standard 3 is secured by suitable fastenings 4 to the base. If desired, a small L-shaped brace 5 may be employed to increase the rigidity of the structure, this brace being secured by the fastenings 4 to the base and being soldered or otherwise secured to the lower portion of the standard 3. This standard may be of any other construction, but I desire to bend the opposite longitudinal 60 edges thereof laterally as indicated at 6 and then inwardly toward each other as indicated at 7, which construction forms a split sleeve in which a vertically adjustable bar 8 is 65 slideable. Secured intermediate its ends to the laterally bent upper end 9 of said standard is a cross arm 10 which co-operates with a second cross arm 11 which is secured intermediate its ends to the front face of the bar 8 adjacent the upper end of the latter. For 70 the purpose of engaging a sign or card, I equip each of the cross arms at its opposite ends with card engaging clips 12. For the sake of low cost of manufacture and to reduce the retail cost of the device, I desire to 75 employ the types of card clips shown. An examination of these parts will disclose the fact that each one is merely a short piece of metal bent between its ends to form a U, which straddles and is secured in any suitable way to the arms 10 and 11. In order 80 that these clips will effectively grip the card, I arrange them in opposed relationship, that is, I extend the engaging portions of the clips on the lower arm 10 upwardly and the clips 85 on the other arm downwardly and toward the just described clips. By off-setting the upper end 9 of the standard and securing the arm 10 thereto, the latter and the upper arm 11 become vertically aligned so that the 90 card may be easily placed between them and held against possible displacement. Any suitable means such as a set-screw 14 may be employed for holding the parts in the position to which they have been moved to 95 accommodate different sizes of signs.

The manner of using the device is entirely obvious and it is not thought that a description is necessary.

From the foregoing description there will 105 be seen that I have perfected an extremely simple and effective sign-holder which will permit various sizes of signs and cards to be supported thereby. The device consists of extremely few and inexpensive parts, 110 and it is extremely easy to make use of.

It is to be understood that the form of

my invention herein shown and described is to be taken as a preferred form of same, and that various minor changes in the shape, size, and arrangement of parts may 5 be resorted to without departing from the spirit of the invention or the scope of the subjoined claims.

I claim:

1. A sign holder comprising a base, a 10 standard rising therefrom, having its opposite longitudinal edges directed laterally in a rearward direction and then inwardly toward each other, forming a split sleeve, the upper end of this standard above said 15 flanges being relatively narrow and offset forwardly, a horizontal cross-arm secured to said off-set portion having its rear face flush with the rear face of the standard, card engaging means carried by the cross- 20 arm, a bar telescoping into said split sleeve, and card engaging means at the upper end of said bar.
2. A sign holder comprising a base, a

standard rising therefrom, having its opposite longitudinal edges directed laterally in 25 a rearward direction and then inwardly toward each other, forming a split sleeve, the end of this standard above said flanges being relatively narrow and off-set forwardly, 30 a flat faced horizontal cross-arm secured intermediate its ends to said offset portion, its rear face being flush with the rear face of the standard, U-card clips at the opposite ends of said cross-arm, a vertical rod of 35 rectangular cross-section telescoping into the flanges of the standard and bearing against the rear face of said cross-arm, a second cross-arm of the same length as the first named arm, being secured intermediate its ends to the upper end of said vertical 40 rod, and inverted U-clips on this arm opposite the first named clips.

In testimony whereof I have hereunto set my hand.

MICHAEL J. DEMUTH.
